UNITED STATES PATENT OFFICE.

ADAM J. FUNSCH, OF BROOKLYN, NEW YORK.

PENCIL SHARPENER.

1,420,539.

Specification of Letters Patent. Patented June 20, 1922.

Application filed September 2, 1920. Serial No. 407,716.

To all whom it may concern:

Be it known that I, ADAM J. FUNSCH, a citizen of the United States of America, residing at Brooklyn, in the county of Kings 5 and State of New York, have invented new and useful Improvements in Pencil Sharpeners, of which the following is a specification.

The object of the invention is to provide a pencil sharpening device particularly adapted for use in drafting offices or rooms wherein pencil points of different forms or types are necessary in connection with the work which involves the use not only of pencils 15 but of leads for compasses and the like, and with this object in view, the invention consists in a construction and combination of parts, of which a preferred embodiment is shown in the accompanying drawings, 20 wherein:—

Figure 1, is a plan view of an apparatus embodying the invention with the covering or casing omitted.

Figure 2, is a horizontal sectional view 25 of the same.

Figure 3, is a vertical sectional view on the plane indicated by the line 3—3 of Figure 2.

Figure 4, is a view partly broken away of 30 the outer casing of a lead holder adapted for use in connection with the apparatus.

Figure 5, is a view of the interior lead holding tube.

Within a suitable casing or housing 10 which is preferably divided by transverse partitions 11 into compartments there is mounted the stock sharpening mechanism consisting of a stationary master gear 12 supported by a partition 13 and a revolvable 15 yoke 14 upon the parallel arms of which are revolvably mounted the conical cutters 15 having pinions 16 which mesh with the master gear 12 which is internally toothed to the end that when the yoke is rotated by 20 means of its spindle 17 mounted in a suitable bearing in the front wall of the casing as by means of a detachable crank 18, the cutters are rotated to act upon the wooden stock of a pencil indicated at 19. The cutters 15 are spaced apart at their bases sufficiently to avoid the contact with the lead 25 of the pencil which is thus left unsharpened or unreduced as indicated in Figure 2, the partition 13 being provided with a suitable 30 opening 21 in which the pencil may be pro-

jected during the sharpening or reducing of the stock.

The pencil is held in proper position in relation to the cutters by means of a clamp 22 of which the jaws are held in engagement 60 with the inserted pencil by means of a spring 23, said jaws being operable by the manipulation of a finger hold 24 projecting to the exterior of the casing.

The rear ends of the yoke 14 are headed 65 as shown at 25 for engagement with a guide 26 secured to the rear wall of the casing and the arms of the yoke are connected at intermediate points by a transversely disposed bar 27 provided with a seat 28 in registration with an opening 29 in the rear wall of the casing to receive the pencil and hold it against vibration during the operation of the cutters thereon.

In one of the adjacent compartments of 75 the casing there is located a pencil point sharpening means consisting of the oppositely revolvable cylindrical members or rolls 30 having roughened surfaces, the spindles 31 of said rolls being provided with intermeshing gears 32 serving to cause rotation of the rolls in opposite directions, there being an operating crank 33 connected with one of the spindles to permit of imparting rotary motion to the same. Carried by the 80 lid or cover 34 of the casing in operative relation to an opening 35 therein, is a pencil clamp 36 and a limiting bracket 37 having a guide opening 38 for the reception of the reduced or tapered portion of the stock 90 of a pencil inserted therein. By means of this rigid sharpening means, a wedge point may be applied to the pencil for use in fine lines in connection with drafting, such a point being frequently required in connection with both pencils and leads designed for use in compasses. Obviously when a lead 95 independently of the pencil is to be sharpened, it should be arranged in a holder such as indicated in Figures 4 and 5, consisting of 100 a shell 39 having an encased tube 40 provided with the spring jaws 41 for clamping the lead when forced into the tapered portion 42 of the shell. The tube is threaded as at 43 for engagement with corresponding 105 interior thread 44 in the shell and the turning of the tube may be effected by means of a thumb head 45 milled as indicated.

In another compartment of the casing 110 there is arranged a lead reducing or sharp-

ening device consisting of a revolvable yoke 46 having a spindle 47 to which is attached an operating crank 48, the arms of the yoke being headed as indicated at 49 for engagement with an annular guide 50 supported by a partition 51 in the compartment. The arms of said yoke carry the coned abrading or sharpening elements 52 disposed in such relation that when the yoke is turned. 10 a pencil 53 being arranged in the holding clamp 54, a sharp or cone point is formed thereon; while in still another compartment of the casing there is mounted a spindle 55 also having an operating crank 56 and carrying a single abrading cone 57 disposed in operative relation with a pencil socket 58 arranged in registration with a pencil clamp 59 for holding the pencil as indicated at 60 and designed to form a chisel 15 point on the lead portion of the pencil.

Means for preventing the insertion of the pencil far enough to bring the point or lead sharpening means into engagement with the stock of the pencil, or in other words, the 20 wooden bark thereof, are provided in connection with the device above described. For instance, in transverse relation of the arms of the yoke 46 there is employed a limiting bar 61 having a tapered opening 62 25 which receives the tapered portion of the stock while a similar bar 63 is carried by the casing in operative relation with the pencil socket 58 for a similar purpose.

Thus by means of the mechanism described, the wooden stock of the pencil may 30 be sharpened without affecting the shape of the lead after which the lead may be reduced to a point of the desired shape, that is to say, either wedge-shaped or coned or 35 chiselled to suit the purpose for which the pencil is to be employed and the independent lead intended for use in connection with compasses and the like may be correspondingly reduced or pointed by first positioning 40 the same in the holder provided as a substitute for the usual pencil stock and adapted to maintain the lead in proper relation to the cutting means.

The operating cranks or handles by which 45 the spindles of the different parts of the apparatus are adapted to be rotated are preferably detachably secured to the spindles by

means of removable pins 64 engaging bifurcated extremities 65 of the spindle of the reduced extremities of the crank arms as 55 shown at 66 to permit of storing said cranks or handles within the casing when the apparatus is not in use as a means of economizing space.

The invention having been described, what 60 is claimed as new and useful is:—

1. A pencil sharpening apparatus having a revolvable yoke provided at one end with a spindle and having parallel arms engaged at their free ends with an annular guide, 65 rotatable cutters mounted upon the arms of said yoke, and means for communicating rotary motion to the spindle of the yoke.

2. A pencil sharpening apparatus having a revolvable yoke provided at one end with 70 a spindle and having parallel arms engaged at their free ends with an annular guide, rotatable cutters mounted upon the arms of said yoke, a limiting bar disposed in transverse relation with the arms of the yoke and 75 having a taper opening which receives the tapered portion of the pencil stock, and means for communicating rotary motion to the spindle of the yoke.

3. A pencil sharpening apparatus having 80 a revolvable yoke provided with spaced parallel arms formed at their extremities with heads, an annular guide with which said heads engage, a transverse element spanning the arms of the yoke intermediate their 85 length, cutters mounted on the arms of the yoke, a spindle extending from the yoke in a direction opposite the arms, and a crank for imparting rotary motion to the 90 spindle.

4. A pencil sharpening apparatus having a revolvable yoke provided at one end with a spindle having its parallel arms engaged at their free ends with an annular guide, 95 rotatable cutters mounted upon the arms of said yoke, means for communicating rotary motion to the spindle of the yoke, and pencil holding means including a clamp for supporting a pencil with its extremity in co-extensive relation with the axes of the orbits 100 of said cutters.

In testimony whereof he affixes his signature.

ADAM J. FUNSCH.
